UNITED STATES PATENT OFFICE.

EARL G. WATROUS, OF CHICAGO, ILLINOIS.

FLUSHING-VALVE.

1,379,231.

Specification of Letters Patent. Patented May 24, 1921.

Application filed January 29, 1917. Serial No. 145,262.

To all whom it may concern:

Be it known that I, EARL G. WATROUS, a citizen of the United States, residing at Chicago, in the county of Cook and State of Illinois, have invented certain new and useful Improvements in Flushing-Valves, of which the following is a specification.

My invention relates to what are known as slow closing or flushing valves for water closets and the object thereof is to provide a simple, efficient and reliable valve of this character.

In the drawings, Figure 1 is a sectional elevation of a flushing valve embodying my invention; Fig. 2 a top plan view thereof; Fig. 3 a sectional elevation on the line 3—3 of Fig. 2; and Fig. 4 a sectional elevation of a modified form of construction as regards the manipulative means for operating the valve.

Referring to the embodiment of my invention as illustrated in Figs. 1, 2 and 3 the valve casing is formed in two parts or sections, an upper section 1 and a lower section 2 which are secured together at meeting marginal flanges in suitable manner as by means of the screws 3, these two sections clamping between them at such flanges a flexible diaphragm 4 of suitable material.

30 The casing is provided with an inlet pipe connection 5 and an outlet pipe connection 6.

The interior of the lower section 2 of the casing is provided with a centrally arranged casing 7 which forms a discharge chamber 8 open at all times to the discharge connection 6. Within this chamber is arranged the main or controlling valve which controls the supply of the flushing water through the valve mechanism and to the water closet.

40 This main valve comprises the flexible diaphragm 4 together with a disk 9 and a sleeve 10, the latter passing through such disk and diaphragm and being secured to a follower plate 11 by screwing into a centrally screw-threaded socket thereof. By preference, this plate is weighted in suitable manner to assure proper closing of the discharge valve. The sleeve 10 is provided intermediate its length with a marginal flange 10^b bearing against the under side of the disk 9 whereby the latter is held clamped in position onto the under side of the diaphragm. The follower plate is preferably

of the formation shown in Fig. 1 with its extreme upper edges 11^a straight so as to 55 bear against and be guided by the inner walls of the casing section 1. The sleeve 10 is provided at its lower end with a marginal flange 10^b which is of the same diameter as the disk 9 and is adapted to fit in and substantially close the upper end of the diaphragm chamber when the main valve is in its uppermost position.

The main valve is guided in its movements by the provision of a central tube 12 65 which at its lower end screws into a socket 8^a of the discharge chamber and extends upwardly within the sleeve 10 so that the latter may slide up and down thereon. If desired, this tube may be cast integral with 70 casing 7. This tube is provided with a lateral port 12^a communicating with the bottom of the discharge chamber and also with the interior of the tube as well as with the interior of the socket of the follower 75 plate 11. The purpose of this arrangement is to permit of the free passage or escape of water to and from the space above such tube and thereby prevent the formation of a vacuum.

80 The inlet chamber 13 below the diaphragm is in constant communication with the chamber 14 above the diaphragm by means of the by-pass 15 which is regulated by means of the regulating valve 16 of the 85 usual form with the result that the rate of flow of water through such by-pass can be regulated.

The manipulative means for operating the relief valve may be a foot and hand control 90 combined as shown in Fig. 1, or a hand control, as shown in Fig. 4.

Referring to the form of control shown in Fig. 1 the pedal lever 17 is pivoted to the top section of the casing on the pin 18 and 95 is held to normal position by means of the spring 19 coiled around the two stop members 20 and 21 projecting from the lever and casing respectively, and adapted to limit the downward or operative movement 100 of such lever. The top of the section 1 is provided with a chamber 22 communicating with the top of chamber 14 through the port 23 and also with the discharge connection 6 through the passage 24. The port 23 105 is controlled by a disk valve 25 which is

secured to a flexible diaphragm 26 by means of the screw 27 which passes through the valve and diaphragm and screws into a plunger 28 reciprocable in a central opening in a plug 29 which screws into the top of section 1. The lever 17 is provided on its under side with a depending finger 30 which is adapted to bear upon this plunger 28 and to keep the same depressed and consequently 10 the valve 25 seated.

Describing the operation of the valve the water under pressure is always present in the chamber 13 and the chamber 14 is supplied with the same pressure through the by-pass 15. Under this condition the parts are 15 in their normal position shown in Fig. 1. When the operator operates the lever 17 by either pressing his foot upon the left-hand end thereof or pulls upwardly thereupon by 20 means of the finger-hold or hook 31 the plunger 28 is relieved of the pressure of the finger 30 thereupon with the result that the water pressure in the chamber 14 will open the valve 25 and such water will escape 25 through the port 23, chamber 22 and passage 24 to the discharge connection 6. As a further result the preponderance of pressure in the chamber 13 will move the diaphragm and its attached parts upwardly until the 30 flange 10^b is in position to close the upper end of the discharge chamber 8. When the pressure on the lever 17 is removed the valve 25 will be closed and the water under 35 pressure will pass through the by-pass 15 and into the chamber 14 whereupon the diaphragm will be moved downwardly at a slow rate determined by the rate of flow through such by-pass. The water in the chamber 13 will flow into the discharge 40 chamber as soon as the flange 10^b has been lowered below the top opening thereof and the water will thereupon pass through such discharge chamber and through the discharge connection. When the diaphragm 45 reaches its lowermost position the communication between chambers 13 and 8 will be closed by the disk 9 and also by the diaphragm itself pressing upon the top edge of the controlling chamber.

50 Referring to the hand control shown in Fig. 4, the same comprises a handle 32 to whose lower end is secured by screwing thereonto a collar 33 having an outer marginal flange 33^a. This flange fits within the 55 upper end of a casing 34 which is secured to the top of the upper section 1' of the main casing corresponding to the section 1 of the other form of construction. This flange and consequently the handle is retained 60 within the casing by reason of the inturned end flange 34^a. Within this casing 34 is arranged a disk 35 which is spring-pressed upwardly or outwardly by means of a coiled spring 36. This disk is secured to a valve

stem 37 which extends downwardly through 65 the stuffing box 38 and is provided at its lower end with a head 39 constituting a valve adapted to govern the port 40 which leads from the chamber 14 to the passage 24. A light spring 41 is interposed between the 70 disk 35 and the inner end of the handle 32 in order to maintain such handle in its normal raised position shown. When this handle is tilted to one side the depressed side of the flange 33^a will contact the disk 35, forcing the latter downwardly against the tension of the spring 36 and opening the relief valve 39 with the same result as the opening 75 of the valve 27 in the other form of construction. When the pressure of the handle 80 is released the springs 36 and 41 will restore the movable parts to their normal position.

I claim:

1. In a flushing valve, a casing having inlet and outlet water-flow openings, an effectively-imperforate diaphragm dividing it 85 into a water-flow section and a control chamber, said casing having two by-passes through its wall from the control chamber respectively to the outlet portion and to the 90 inlet portion of the water-flow section and also having internal walls dividing the water-flow section into inlet and outlet portions, one of them including a central chamber which is relatively deep along a line 95 perpendicular to the diaphragm is closed at its bottom, with the appurtenant water-flow opening leading laterally into it and which has an opening toward the diaphragm for communication between the inlet and outlet 100 portions, a manually operable valve for the by-pass to the outlet portion, and an automatic valve carried by the diaphragm, extending through said opening into and 105 guided in the central chamber, and having two axially spaced valving portions which, when said valve is closed, are respectively 110 above and below the top of said water-flow opening and either of which may control the diaphragm moves.

2. In a flushing valve, the combination of a casing having water inlet and outlet openings, a diaphragm making constant division of the casing into a water-flow section and a 115 control chamber, said casing having two by-passes through its wall from the control chamber respectively to the outlet portion and to the inlet portion of the water-flow section and also having internal walls dividing the water-flow section into inlet and outlet portions, one of them including a central chamber relatively deep along a line 120 perpendicular to the diaphragm and having an opening toward the diaphragm for effecting communication between the inlet and outlet portions, a manual valve for the first-mentioned by-pass, a valve carried by the 125

diaphragm extending through said opening into the central chamber and having two axially spaced valving portions either of which may control said opening accordingly 5 as the diaphragm moves, and a guide member fixed within said central chamber and penetrating said valve.

3. In a flushing valve, the combination of a casing having water inlet and outlet openings, a diaphragm making constant division of the casing into a water-flow section and a control chamber, said casing having two by-passes through its wall from the control chamber respectively to the outlet portion 15 and to the inlet portion of the water-flow section and also having internal walls dividing the water-flow section into inlet and outlet portions, one of them including a central chamber relatively deep along a line 20 perpendicular to the diaphragm and having an opening toward the diaphragm for effecting communication between the inlet and outlet portions, a manual valve for the first-mentioned by-pass, a valve carried by said 25 diaphragm having an axially recessed stem extending into said central chamber, and a rod fixed in said central chamber upon which said stem is mounted to slide.

4. In a flushing valve, the combination of a main casing, a diaphragm dividing the casing into a pressure chamber and a controlling chamber, means for by-passing water under pressure from the pressure chamber to the controlling chamber, means 35 for releasing water under pressure from the latter chamber, an interior casing situated substantially centrally of the pressure chamber and having an inlet opening communicating with the pressure chamber and having 40 an outlet opening, and a slow closing valve mechanism secured to the diaphragm and operable in the interior casing to govern its inlet opening, said valve mechanism comprising a disk normally closing said inlet 45 opening, a sleeve in such interior casing and mounted upon the diaphragm, and a rod within the latter casing on which the sleeve is mounted to slide.

5. In a flushing valve, the combination of a main casing, a diaphragm dividing the casing into a pressure chamber and a controlling chamber, means for by-passing water under pressure from the pressure chamber to the controlling chamber, means 55 for releasing water under pressure from the latter chamber, an interior casing situated substantially centrally of the pressure chamber and having an inlet opening communicating with the pressure chamber and having an outlet opening, and a slow closing valve mechanism secured to the diaphragm and operable in the interior casing to govern its inlet opening, said valve mechanism comprising a disk normally clos-

ing said inlet opening, a sleeve in such interior casing and secured to and clamping the disk to the diaphragm, and a fixed rod within the latter casing on which the sleeve is mounted to slide, said sleeve having a flange for closing the inlet opening when 70 the valve is operated.

6. In a flushing valve, the combination of a main casing, a diaphragm dividing the casing into a pressure chamber and a controlling chamber, means for by-passing water 75 under pressure from the pressure chamber to the controlling chamber, means for releasing water under pressure from the latter chamber, an interior casing situated substantially centrally of the pressure chamber 80 and having an inlet opening communicating with the pressure chamber and having an outlet opening, and a slow closing valve mechanism secured to the diaphragm and operable in the interior casing to govern its 85 inlet opening, said valve mechanism comprising a disk normally closing said inlet opening, a sleeve in such interior casing and clamping the disk to the diaphragm, and a rod within the latter casing on which the 90 sleeve is mounted to slide, said rod having a relief passage communicating with the interior casing and the inner end of such sleeve.

7. In a flushing valve, the combination of a main casing, a diaphragm dividing the casing into a pressure chamber and a controlling chamber, means for by-passing water under pressure from the pressure chamber to the controlling chamber, means 95 for releasing water under pressure from the latter chamber, an interior casing situated substantially centrally of the pressure chamber and having an inlet opening communicating with the pressure chamber and having 100 an outlet opening, and a slow closing valve mechanism secured to the diaphragm and operable in the interior casing to govern its inlet opening, said valve mechanism comprising a disk normally closing said inlet 105 opening and arranged on one side of the diaphragm, a follower plate on the other side thereof, and a sleeve passing through the disk and diaphragm and secured to the plate to clamp the disk to the diaphragm 110 and a rod fixed within the interior casing entering said sleeve to guide the same.

8. In a flushing valve, the combination of a main casing, a diaphragm dividing the casing into a pressure chamber and a controlling chamber, means for by-passing water under pressure from the pressure chamber to the controlling chamber, means for releasing water under pressure from the latter chamber, an interior casing situated 115 substantially centrally of the pressure chamber and having an inlet opening communicating with the pressure chamber and hav-

ing an outlet opening, and a slow closing valve mechanism secured to the diaphragm and operable in the interior casing to govern its inlet opening, said valve mechanism comprising a disk normally closing said inlet opening and arranged on one side of the diaphragm, a follower plate on the other

side thereof, and a sleeve passing through the disk and diaphragm and secured to the plate to clamp the disk to the diaphragm, and a tube secured within the interior casing and acting as a guide for the sleeve.

EARL G. WATROUS.
